UNITED STATES PATENT OFFICE.

JESSE KAUFMAN, OF NEW YORK, N. Y.

COLLAR.

1,153,693.

Specification of Letters Patent. Patented Sept. 14, 1915.

Application filed March 14, 1913. Serial No. 754,171.

To all whom it may concern:

Be it known that I, JESSE KAUFMAN, a citizen of the United States, and resident of the borough of Manhattan, city, county, and State of New York, have invented certain new and useful Improvements in Collars, of which the following is a specification.

This device is intended as an improvement in the construction of collars that will obviate the necessity of the employment of the ordinary back button as a means for securing the collar to the band of the shirt.

To secure a collar under ordinary conditions it is considered necessary to provide a plurality of buttons and the necessary number of button holes. The number of buttons usually employed is two each of which is arranged in the collar band, one at the front and the other at the back, care being taken that the buttons be arranged as nearly diametrically opposite as possible. The collar adapted to be secured upon these buttons is usually provided with three button holes, one at the back and one at each free front end of the collar, all of which are well adapted to be secured to the buttons arranged adjacent thereto. This method and arrangement has been found fairly satisfactory, but because of certain disadvantages which are more apparent in the fold collar than in any other I have endeavored to secure my collar without the employment of what is commonly called the back button, and by the arrangement that I am about to describe I secure a more flexible connection between the collar and the shirt, overcome the objectionable bulkiness due to the presence of the button and provide an unobstructed passage for the neck band of the cravat allowing it to slide more easily and to be adjusted more readily.

The following is what I consider the best means of carrying out this invention.

The accompanying drawings form a part of this specification, in which:

Figure 1 shows an ordinary collar constructed with my improvement. Fig. 2 shows a section through the tab.

Similar reference numerals indicate like parts in all the figures where they appear.

At 1, I have shown an ordinary collar which in this instance is a fold collar having outer and inner parts and ordinary securing tabs 2 and 3. As I find it necessary in describing my device to continually refer to the inner band of the collar I will indi-

cate that part by the reference character 4. This band may or may not be formed integral with the tabs 2 and 3 and in these tabs I provide the ordinary button holes 5 and 6. Thus far I have described a collar well known and fully appreciated, and such a collar is usually provided with a back button hole.

At about the point adjacent to where the back button hole is usually produced I provide two vertical slits 7 and 8 spacing them definite distances apart and at a convenient height I connect these slits 7 and 8 by a longitudinal slit 9 thus producing a tab 10 the upper end of which is free to be bent outward or inward, but the lower end of which will be formed integral or well secured to the inner band 4.

It is my intention to surround the slits 7, 8, and 9 with the proper lines of stitching 11 and 12 thus assuring that the edges of the tab 10 and the adjacent edges of the band 4 will not fray.

The inner band 4 of a double collar is usually made two ply, that is of two thicknesses of material, should the tab formed integral with such a band be found less firm than is desirable the tab when divided from the band 4 may be provided with a filler before the stitching takes place. I believe however that this will not be necessary even with collars of a cheaper grade.

For use with soft collars or when formed integral therewith my tab may be found too pliable to produce a secure fastening because of the absence of starch in collars of this kind and description. I may find it convenient therefore to add to my collar a means for insuring the desirable firmness in the tab.

At 20 I show a metallic binding secured on the three edges of the tab 10, this binding may be formed of thin sheet metal folded upon itself as shown at 21, and having its free edges crimped, so that they will form a close engagement into and with the edge of the cloth over which they are to be placed. As shown at 22, my tabs may be provided with the ordinary button hole although I do not consider this absolutely necessary as it will in no way add to the efficiency of my device.

From the foregoing it is believed that the operation of my device will be well understood but I will however briefly detail it. A collar having been constructed as shown

- and described, it is laundered in the ordinary manner, the tab 10 is ironed flat so that when the collar is completed and laundered the tab does not project out of common circle or plane of the part 4. When however the collar is desired for use the neck band of the cravat is placed in the ordinary condition and the tab 10 bent slightly outward, it may then be readily engaged with the ordinary loose and projecting part of the collar band of the shirt, the front and free ends of the collar are secured to a button in the ordinary manner and the collar is in position for use.
- 15 Modifications may be made within the scope of the appended claim without departing from the principle or sacrificing the advantages of this invention.

Having carefully and fully described my

invention what I claim and desire to secure 20 by Letters Patent is:—

A device of the character described comprising a collar having ordinary tabs and button holes formed therein and an additional tab at about mid-length said collar 25 formed integral therewith and means for stiffening said tab adapting it to assist in the securing of said collar, said tab being provided with a button hole and a metallic binding around the free sides of said tab, 30 for the purpose set forth.

Signed at New York city, in the county of New York, and State of New York this 8 day of March 1913.

JESSE KAUFMAN.
